DESIGN FOR A BELT FOR WEARING APPAREL

Bernell J. Bequette, Arvada, Colo.

Application January 9, 1948, Serial No. 143,631

Term of patent 7 years

(Cl. D3—10)

To all whom it may concern:

Be it known that I, Bernell J. Bequette, a citizen of the United States of America, residing at Arvada, in the county of Jefferson and State of Colorado, have invented a new, original, and ornamental Design for a Belt for Wearing Apparel, of which the following is a specification, reference being had to the accompanying drawing, forming a part thereof.

In the drawing:

Fig. 1 is a side view of a belt for wearing apparel, illustrating the new design;

Fig. 2 is a face view of a single element of the belt; and

Fig. 3 is an edge view of the element of Fig. 2.

I claim:

The ornamental design for a belt for wearing apparel, as shown.

BERNELL J. BEQUETTE.
